UNITED STATES PATENT OFFICE

2,239,178

REFRIGERATING APPARATUS

John A. Conrad, Cincinnati, Ohio, assignor to
The Crosley Corporation, Cincinnati, Ohio, a
corporation of Ohio

Application March 10, 1937, Serial No. 130,136

6 Claims. (Cl. 62—118)

My invention relates specifically to the "receiver evaporator" in refrigerating apparatus of the intermittent absorption type.

In refrigerating apparatus operative on the intermittent absorption principle, a refrigerant such as ammonia is employed and an absorbent such as water. The strong liquor or concentrated solution of ammonia in the water is boiled in a vessel commonly called a generator. This same vessel usually functions as an absorber. Heat is applied during the heating cycle to cause the boiling off of the refrigerant. The refrigerant, in gaseous form, passes under pressure to a condenser and receiver in which the gaseous refrigerant is condensed to a liquid and, pending its use during the evaporation cycle, stored. Toward the end of the heating cycle the liquified refrigerant is transferred from the receiver to the inner shell of the evaporator in which the expansion of the refrigerant to gaseous condition takes up heat which induces such cooling as is required for freezing ice cubes and generally cooling the cooling chambers of the refrigerator.

In some apparatus of the intermittent absorption type the receiver acts also as the evaporator, but in the particular combination with which I shall describe my invention, the receiver is a vessel separate from the evaporator.

It is one object of my invention to employ a siphon between the receiver and the evaporator to cause the liquid refrigerant trapped in the receiver, to be transferred substantially completely to the evaporator, once the cycle is started.

Another object is the provision of a chamber surrounding the ice cube compartment which is filled with a gaseous refrigerant such as sulphur dioxide, said refrigerant causing a blanket of gas between bottom of evaporator and liquid level of refrigerant surrounding ice cube compartment so that during heating cycle a minimum amount of heat will be transferred from warm gas in evaporator to ice cube compartment, and which also, during the evaporating cycle will act as a secondary refrigerating system, thereby cooling and freezing the ice cube compartment.

Another object of my invention is the provision of a return tube from the evaporator to the generator absorber which is so constructed and arranged and so supplied from a trap or sump that when condensed refrigerant is received, it will be transferred to the absorber but that expanded refrigerating gas will also return to the absorber through this same tube.

Another object of my invention is the establishment of a secondary refrigerating system in

5 a compartment surrounding the ice cube chamber in which an exposed chilled surface of the compartment, cooled by the expansion of the primary refrigerant, in this example liquid ammonia, will induce a circulation of the secondary refrigerant which will probably pass through the cycles of condensation and expansion necessary to refrigeration.

10 The above objects and other objects to which reference will be made in the ensuing description, I accomplish by that certain combination and arrangement of parts of which I have illustrated a preferred embodiment.

Referring to the drawing:

Figure 1 is a diagrammatic sectional view of the refrigerating apparatus.

Fig. 2 is a sectional view of the evaporator taken along the lines 2—2 of Fig. 1.

Fig. 3 is a sectional view of the refrigerator similar to that in Fig. 2, excepting that the operation of the secondary refrigerating system is diagrammatically illustrated.

The generator absorber is illustrated at 1. At one end of the generator absorber, there is a dome 2 containing the usual rectifying apparatus. 25 A tube 3 permits the gasified ammonia and liquor entrained therewith to pass into the drum 4. From the drum 4, a tube 5 provides an outlet for the expanded gases which pass upwardly through the entrained liquor trapped in the dome. An 30 overflow 1 drains the dome 2 after the entrained liquor has filled up the dome to the level of the top of the tube 1. The overflow through the tube 1 drains back into the still absorbent.

35 The apparatus also acts as a separator for the gasified refrigerant.

From the top of the dome 2, a tube 8 passes to the condenser coil 9 which is shown as arranged in a tank 10, cooled with some cooling liquid such as water.

40 A tube 11 is connected to the discharge or outlet from the condenser coil 9 and this drains the condensed fluid into the receiver 12.

In the receiver 12 there is a return bent tube 45 13 through which the condensed refrigerant passes to the evaporator 14.

To prevent the liquor being forced by pressure from the sump 15 into the evaporator 14, I have provided a pressure relief tube 16 having an inlet 17 at the top of the tube. Pressure is equalized between the receiver 12 and the evaporator 14 by means of the tube 16 until the level of condensed refrigerant, indicated in dotted lines in Fig. 1, has reached the inlet 17 to the tube 16. Then 50 when the inlet 17 of the tube 16 is sealed, the

liquor is forced by the pressure in the receiver 12 into the evaporator 14.

After the receiver 12 has been filled to the level of the inlet 17 and has started to siphon into the evaporator, the siphoning action continues until substantially all the condensed refrigerant in the receiver 12 has siphoned over into the evaporator.

The evaporator 14 has a false bottom 18 having a sump 19 at a low point therein. The small opening 20 permits the condensed liquid to feed either in a very fine string or drop by drop into the evaporating chamber 21 which is formed by the space in the evaporator 14 below the false bottom plate 18. The bottom of the evaporator 14 has a sump 22 from which a tube 23 permits the expanded gas and unexpanded liquor to pass down through the tube 23 into another dome 24 arranged at the end of the generator opposite the dome 2.

A tube 25 drains the expanded gas and unexpanded liquor which passes down the pipe 23 back into the generator absorber.

During normal operation, there will be some entrainment of unevaporated refrigerant through the pipe 23 into the dome 24, but such unevaporated refrigerant will fill in the dome 24 to the level of the top of the tube 25 and as soon as any additional refrigerant is entrained, it will be returned to the weak liquor in the generator 1.

A pressure equalizing tube 26 connects the dome 24 with the dome 2. This prevents the building up of too much pressure on the pressure side of the system.

The ice-cube chamber, as indicated at 27, is formed by a rectangular shell which is set into the end walls of the compartment 28, the end joints being preferably formed by a welding operation.

The compartment 28 is secured to the evaporator 14 so that the walls thereof are welded to the evaporator in substantially the position illustrated in Figs. 2 and 3. Consequently the lower half of the evaporator 14 is set into the top wall of the compartment 28.

Within the compartment 28 a secondary refrigerating system is set up. A preferred refrigerant is sulphur dioxide. In the illustration in Fig. 2 the system is shown during the generating cycle at which time, the evaporator 14 becomes warm. The lower wall, were it not for the presence of the sulphur dioxide gas acting as an insulator rapidly exchanges its heat to the walls of the cooling compartment 27. As the sulphur dioxide gas is warmed up, the warm gas rises to the top of the compartment 28 and an atmosphere of cool sulphur dioxide liquid remains in the lower portion of the compartment 28 which prevents heat being transferred from the evaporator.

During the evaporating cycle illustrated diagrammatically in Fig. 3, the condensed refrigerant, ammonia, drips through the small opening 20 and evaporates in the chamber. This action chills the lower wall of the evaporator. The sulphur dioxide gas coming into contact with the chilled lower wall of the evaporator will be condensed into liquid form and drip down and strike the liquid level above the top wall of the chamber 21. This will start circulation of cold liquid around chamber 21 and warm gas to bottom of evaporator in the direction of the arrows illustrated.

It may be that the exact action which I have

described will not occur. In any event, the chilled bottom wall of the evaporator 14 will cause a circulation of the sulphur dioxide gas, the cold gas passing down and striking the top wall of the chamber 21 and the warm gas passing up along the outer walls of the chamber 28.

Having thus described my invention, what I claim as new and desire to secure by Letters Patent is:

- 10 1. In refrigeration apparatus of the intermittent absorption type in combination with the evaporator, a shell spaced from the lower wall of said evaporator forming a secondary evaporator; and a drip opening at a low point in said shell to permit the gravity flow of condensed refrigerant from above said shell into said secondary evaporator.
- 15 2. In refrigeration apparatus of the intermittent absorption type an evaporator having a shell interposed therein forming a receiver compartment in the portion above the shell and a secondary evaporator below said shell and means including a restricted opening at a low point in said shell for controlling the introduction of liquid refrigerant from said receiver compartment into said secondary evaporator.
- 20 3. In refrigeration apparatus of the intermittent absorption type an evaporator having a shell interposed therein forming a receiver compartment in the portion above the shell and an evaporating chamber below said shell and means for controlling the introduction of liquid refrigerant from said receiver compartment into said evaporating chamber comprising a restricted orifice at a low point in said receiver, said portion below said shell being housed in a gaseous atmosphere within which a freezing chamber is also housed.
- 25 4. In refrigeration apparatus of the intermittent absorption type an evaporator having a shell interposed therein forming a receiver compartment in the portion above the shell and an evaporating chamber below said shell and means for controlling the introduction of liquid refrigerant from said receiver compartment into said evaporating chamber comprising a restricted orifice at a low point in said receiver, said portion below said shell being housed in a gaseous atmosphere within which a freezing chamber is also housed, said gaseous atmosphere comprising sulphur dioxide.
- 30 5. In refrigerating apparatus of the intermittent absorption type, an evaporator having a shell interposed therein forming a receiver in the portion above the shell and an evaporating chamber in the portion below the shell, means for introducing a condensed refrigerant from said receiver to said evaporating chamber, a still absorber and means for returning the refrigerant in both gaseous and liquid form from said evaporator to said still absorber.
- 35 6. In refrigerating apparatus of the intermittent absorption type, an evaporator having a shell interposed therein forming a receiver in the portion above the shell and an evaporating chamber in the portion below the shell, means for introducing a condensed refrigerant from said receiver to said evaporating chamber, a still absorber and means for returning the refrigerant in both gaseous and liquid form from said evaporator to said still absorber comprising a tube having an intake in a sump arranged at a low point in said evaporator.

JOHN A. CONRADY.
